UNITED STATES PATENT OFFICE

JOHN F. HOY, OF MORRISTOWN, PENNSYLVANIA, ASSIGNOR, BY MESNE ASSIGNMENTS,
TO AUTOKRAFT BOX CORPORATION, OF YORK, PENNSYLVANIA, A CORPORATION
OF DELAWARE

BOX SLITTING MACHINE

Application filed August 14, 1928. Serial No. 299,556.

The present invention, generally stated, relates to machinery used in wooden box construction and has more especial relation to a slitting machine as used in cigar box manufacture.

The leading object of the present invention may be said to reside in the provision of a novel form of machine of simple, efficient, and relatively inexpensive construction for the so-called slitting or cutting from an integral structure of multiple height, complete box frames.

A further object resides in the provision of general details of construction and in the arrangement, connection and combination of parts for attaining the results sought by said leading object.

Other and further objects will appear hereinafter.

20 The invention consists of the novel construction hereinafter described and finally claimed.

The nature, characteristic features and scope of the invention will be more fully understood from the following description taken in connection with the accompanying drawings forming part hereof, and in which:

25 Fig. 1 is a view in side elevation of a machine embodying the invention.

Fig. 2 is a top or plan view thereof.

Fig. 3 is a view in cross section taken upon the line 3—3 of Fig. 2.

30 Fig. 4 is a view in elevation of a machine embodying the invention, with certain parts broken away for clearer illustration.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

35 In wooden box manufacture, an integral box frame having four sides and being two

or more times the required height and which frame is calculated to be split into two or more sections is placed upon the table 1 from which table the plunger conveyor 2 takes said box structure to the horizontal, spaced chains 3, which carry said box structure, by means of attached lugs 4, past the saw 5.

The main drive is from the motor 6 through shaft 7 to drive the saw for cutting the box parts. The feed drive is from a motor 51 through shaft 52 to a worm contained within housing 53, which worm drives shaft 45 on which shaft 45 is a sprocket 14 provided with a safety device 10 which slips when the chains 3 jamb or are obstructed. The safety device 10 consists of a spring pressed plunger arranged in a casting carried by sprocket wheel 14, which sprocket wheel is loose on shaft 45. Normally the spring pressed plunger engages a bevelled recess in the circumference of a collar fixed to the shaft 45, and the said spring pressed plunger becomes disengaged from the recess of the collar to permit the shaft 45 to operate without driving the sprocket wheel 14 under overloading of the feed mechanism of the machine. The shaft 45 is provided with a gear 11 which drives another gear 12 having an eccentric pin 13.

35 The sprocket wheel 14 by means of sprocket chain 9 drives another sprocket 15 keyed to a horizontal shaft 16 provided with two bevel gears 17 and 18, which gears mesh with gears 17' and 18' and drive two vertical shafts 19 and 20 provided with two suitable hubs each. These four hubs are provided with sprockets bolted to them, said sprockets having slotted bolt holes to permit advancing or retiring the sprockets so as to keep the lugs fastened to the chains 3 in unison and parallel.

40 These chains 3 travel in a horizontal plane around idlers 25 which are adjustable as at 26 for tightening. The adjustment is made by setting out the support bars and clamping same to place by means of screws. The lugs 4 on the chains 3 carry the box parts past the saw 5 which splits them. The chains 3 carry the box parts through the guides 56 on table 1 under the guides 55 till

the box parts pass through the cutting parts of the saw 5 and are separated. The lugs are bars connecting the two chains, the lower chain being lower than the table top, and the sprocket set below the table top with plates 63 set above them to make a sliding surface for the box. These chains entirely encircle the guides 56 and their supporting members and the box enters the enclosure 10 at a time when no lug interferes. The guide 36 is adjustable two ways: horizontally to guide different width box frames or structures; and to permit as small an opening as possible between itself and the chain lug 15 4 as lug 4 passes guide 36. The guides 56 are adjustable at 54 for different width boxes and one of the guides 56 has spring compensation at 57 for slight variation in the different box parts.

20 After the box parts are split at the front edge of the saw, the box parts are guided by the guides 50 to the end of the table, said box parts being propelled by the next following box part. The guides are adjustable 25 for various sizes of box parts by clamping guide bracket 37 at proper position and the guides 43 keep the saws from again cutting the box parts as the parts pass the rear end of the saw. The guard 41 prevents anything from coming in contact with the saw at its rear as well as holding down the split box parts. The guides 43, it is to be understood in the connection, are set to abut against the saw to deflect the box parts as the 35 same pass the rear end of the saw, thus preventing the saw teeth from again cutting the box parts. The guard 41 is suitably held down, it being understood that it is hinged at its front end to guide 55. The guard 40 41 is hinged to the fixed guard 60, which guard 60 is attached to guide 55.

The saw 5 is mounted with the shaft 44 and motor 6 which drives both on a plate 47 which is mounted on plate 48 by a swivel that permits vertical aligning of the saw. 45 Plate 48 is mounted on plate 49 in such a manner as to permit aligning of the saw 5 horizontally.

The eccentric pin 13 on the gear 12 driven by the gear 11 on the shaft 45 has a link 46 fastened to it which keeps an arm 27 moving forward and backward. This arm 27 is clamped at 28 to a rock shaft 29 to which is fastened another arm 30, having a link 31 which is connected to the sliding plunger 2 which conveys the integral parts from table 1 to a position which enables the chains 3 to continue their motion past the saw 5. The gears and sprockets are designed 55 to keep plunger 2 and lugs 4 in unison.

50 As the plunger 2 pushes the box parts forward they are guided at 36 to direct the box parts to the proper position for the chains 3 to continue their forward motion. As the 55 chains 3 continue forward after the box

parts are separated the box parts travel between guides 50 which are adjustable at 37 for different sizes of boxes.

The saw arbor 44 and motor shaft 7 are connected with a flexible coupling 46 and are mounted on a plate 47 which has adjustment vertically and horizontally to align the saw 5 for a straight cut. The saw 5 revolves in a vertical plane upon horizontal shaft 44. It will be understood that after 75 severing of box parts, bottoms are applied in the usual manner and which forms no part of the present invention.

I am aware that the invention may be embodied in other specific forms without departing from the spirit or essential attributes thereof, and I therefore desire the present embodiment to be considered in all respects as illustrative and not restrictive, reference being had to the appended claims 85 rather than to the foregoing description to indicate the scope of the invention.

What I claim is:

1. In a machine of the character stated, a pair of horizontally disposed endless chains, a second pair of endless chains spaced above the first mentioned pair of chains, said chains being provided with lugs connecting the upper and lower chains to engage and advance a box structure to a cutter for box part slitting, a cutter rotatably mounted in a vertical manner between said pairs of chains, a reciprocating plunger for feeding a box structure to said chains, a horizontal drive shaft upon which said cutter is mounted, a motor for directly driving said shaft, independent means including a motor for driving said chains, and means operatively connected with said chain driving means for operating said reciprocating plunger.

2. In a machine of the character stated, a pair of horizontally disposed endless chains, a second pair of endless chains spaced above the first mentioned pair of chains, said chains being provided with lugs connecting the upper and lower chains to engage and advance a box structure to a cutter for box part slitting, a cutter rotatably mounted in a vertical manner between said pairs of chains, a reciprocating plunger for feeding a box structure to said chains, a horizontal drive shaft upon which said cutter is mounted, a motor for directly driving said shaft, independent means including a motor for driving said chains, means operatively connected with said chain driving means for operating said reciprocating plunger, and guide members for preventing the saw teeth from re-cutting split box parts.

3. In a machine of the character stated, a pair of horizontally disposed endless chains, a second pair of endless chains spaced above the first mentioned pair of chains, said chains being provided with lugs con-

- necting the upper and lower chains to engage and advance a box structure to a cutter for box part slitting, a cutter rotatably mounted in a vertical manner between said pairs of chains, a reciprocating plunger for feeding a box structure to said chains, a horizontal drive shaft upon which said cutter is mounted, a motor for directly driving said shaft, independent means including a motor for driving said chains, means operatively connected with said chain driving means for operating said reciprocating plunger, and guides 50 to guide severed box parts from the machine.
- 15 4. In a machine of the character stated, a pair of horizontally disposed endless chains, a second pair of endless chains spaced above the first mentioned pair of chains, said chains being provided with lugs connecting the upper and lower chains to engage and advance a box structure to a cutter for box part slitting, a cutter rotatably mounted in a vertical manner between said pairs of chains, a reciprocating plunger for feeding a box structure to said chains, a horizontal drive shaft upon which said cutter is mounted, a motor for directly driving said shaft, independent means including a motor for driving said chains, means operatively connected with said chain driving means for operating said reciprocating plunger, guide members for preventing the saw teeth from re-cutting split box parts, and guides 50 to guide severed box parts from the machine.
